UNITED STATES PATENT OFFICE.

ANDREW J. ALLARD, OF RICHMOND, VIRGINIA, ASSIGNOR OF ONE-THIRD TO T. F. GREEN AND ONE-THIRD TO D. R. CREECY, JR., BOTH OF RICHMOND, VIRGINIA.

ELECTRIC TRAIN-CONTROL SYSTEM.

1,100,644.

Specification of Letters Patent. Patented June 16, 1914.

Application filed June 2, 1913. Serial No. 771,316.

To all whom it may concern:

Be it known that I, ANDREW J. ALLARD, of Richmond, in the county of Henrico and State of Virginia, have invented certain new and useful Improvements in Electric Train-5 Control System; and I do hereby declare the following to be a full, clear, and exact description of the invention, such as will enable others skilled in the art to which it 10 appertains to make and use the same.

This invention relates to improvements in electric signaling systems for railroads,—the object of the invention being to provide means for automatically controlling the 15 speed of trains at curves, crossings, bridges or other places where reduced speed of trains is desirable.

With these and other objects in view, the invention consists in certain novel features 20 of construction and combinations of parts as hereinafter set forth and pointed out in the claims.

In the accompanying drawings; Figure 1 is a diagrammatical view of the circuits and 25 devices employed on the rolling equipment; Fig. 2 is a detail view of one of the electromagnetically operated devices which coöperates with the cam on the speedometer shaft; Fig. 3 is an enlarged view of one of 30 the polarized relays; and Figs. 4, 5, 6, 7, 8 and 9 are diagrammatical views showing the track circuits for curves of different degrees.

My improvements contemplate the employment of means on the rolling equipment 35 which operate to control the application and release of the brakes, and partial electric circuits along the railroad at or near curved portions thereof for automatically 40 controlling the operation of said means on the rolling equipment in such manner that the speed of the train will be checked according to the degree of the curve which the train may be approaching or to stop 45 the train when it approaches a sharp curve, such instance, as a curve over which the train should not run at a speed greater than ten miles an hour.

In Figs. 4 to 9, I have shown curved 50 track sections having different degrees of curvature and over which trains should be run at correspondingly different speeds; thus, Fig. 4 may be described as representing a ten-mile curve; Fig. 5 a twenty-mile

curve; Fig. 6 a thirty-mile curve; Fig. 7 a 55 forty-mile curve; Fig. 8 a forty-mile curve, and Fig. 9 a sixty-mile curve. Near each of these curves, certain partial electric circuits are provided for coöperation with partial circuits for controlling the devices on the 60 devices on the rolling equipment approaching the curve.

In each of the Figs. 4 to 9 of the drawings, 1, 2 represent the track rails. Near the ten mile curve shown in Fig. 4, the 65 track rail 1 is connected by a conductor 3 with the negative pole of a battery 4 and the positive pole of this battery is connected by a conductor 5 with a contact rail 6 located near the track rail 1. Another contact rail 7 is located some distance in advance of rail 6 and is connected by a conductor 8 with one pole of a battery 9,—the other pole of this battery being connected, by a conductor 10 with conductor 5 between 75 the contact rail 6 and the battery 4.

In Fig. 5, the contact rail 1 is connected by a conductor 11 with the positive pole of a battery 12, the negative pole of this battery being connected, by a conductor 13 with 80 a contact rail 14 located near the rail 1 and extending around the curved portion of the track.

In Fig. 6, the track rail 1 is connected by a conductor 15 with the negative pole 85 of a battery 16, and the positive pole of this battery is connected by a conductor 17 with a contact rail 18, the latter being located a farther distance from the track rail 1 than are the contact rails 6, 7 and 12, and is preferably extended around the curve of the track.

In Fig. 7, the track rail 1 is connected by a conductor 19 with the positive pole of a battery 20, and the negative pole of this 95 battery is connected, by a conductor 21, with a contact rail 22 located the same distance from the track rail 1 as is the contact rail 18 and also extended around the curve of the track.

In Fig. 8, two contact rails 23—24 are located different distances from track rail 1 and extend around the curve. The contact rail 23 is connected by a conductor 25 with the negative pole of a battery 26 and the 105 negative pole of this battery is connected, by a conductor 27 with contact rail 24.

In Fig. 9, two contact rails 28—29 are

employed, the same as in Fig. 8. The rail 28 is connected by a conductor 30 with the positive pole of a battery 31, and the negative pole of this battery is connected by a conductor 32 with the contact rail 29.

It may be here stated that the contact rails shown in Figs. 4 and 5 and the contact rails 23 and 28 of Figs. 8 and 9, are intended for coöperation with a contact 10. shoe 33 on the rolling equipment, while the contact rails of Figs. 6 and 7 and the contact rails 24 and 29 of Figs. 8 and 9 are intended for coöperation with a contact shoe 34 on the rolling equipment.

15 It will be observed that the circuit connections of the track rail and the contact rails with the batteries are reverse to each other in Figs. 6 and 7, and the same is true regarding the circuit connections of the contact rails and batteries shown in Figs. 8 and 9. The reasons for such arrangements of circuits at the different curves of the road will be hereinafter made apparent.

Provision is shown in the drawings to 25 control the progress of train on curves of six different degrees of curvature, but I do not wish to limit myself to controlling means for this particular number of curves nor to any particular speeds of trains, but 30 for convenience, I have shown six curves and will show and describe circuits and devices for use on the rolling equipment, to coöperate with the track circuits adjacent to such curve. It may also be here stated 35 that my improvements are adapted for use in reducing the speed of trains to any predetermined degree at the approach of crossings, bridges, etc., as well as the approach 40 of curves.

45 In the cab of the rolling equipment, a speedometer 35 is located and its shaft 36 is connected in any suitable manner with an axle of the same. The shaft of the speedometer carries a pointer 37 to register 50 with a scale 38 graduated in miles, and to said shaft, a cam plate or disk 39 is secured and electrically connected. The cam plate or disk 39 is intended for electrical coöperation with six contact rods 40, 41, 42, 43, 44, 45, 46, connected respectively, with the pivoted armature levers 46 of electro-magnets 47, 48, 49, 50, 51, 52.

55 Six polarized relays 53, 54, 55, 56, 57, 58 are provided for controlling the operation of the magnets 47-52, and for the armature lever of each of these relays, an active contact 59 and a dead contact 60 are provided. The armature levers of relays 53-54 are connected by a conductor 61 and the armature levers of relays 55-56 are connected by a conductor 62, while the armature levers of the relays 57-58 are connected by a conductor 63.

60 The active contact 59 of relay 53 is connected by a conductor 64 with one terminal

of magnet 47 and the other terminal of this magnet is connected by a conductor 65 with the positive pole of a battery 66, the negative pole of this battery being connected by a conductor 67 with the conductor 61. The conductor 65 is connected by a conductor 68 with one terminal of magnet 48, and the other terminal of this magnet is connected by a conductor 69 with the active contact 59 of relay 54. One terminal of magnet 49 is connected, by a conductor 70 and the other terminal of this battery is connected by a conductor 71 with the positive pole of a battery 72 while the other pole of this battery is connected, by a conductor 73 with the conductor 62. The conductor 71 is connected by a conductor 74 with one terminal of magnet 50, and the other terminal of this magnet is connected with the active contact 59 of relay 56. One terminal of magnet 51 is connected, by a conductor 75 with the active contact 59 of the relay 57, and the other terminal of this magnet is connected by a conductor 76 with the positive pole of a battery 77, the other pole of the latter being connected by a conductor 78 with the conductor 63. One terminal of the magnet 52 is connected by a conductor 79 with the conductor 76, while the other terminal of this magnet is connected, by a conductor 80 with the active contact 59 of relay 58.

85 One terminal of the coil of relay 53 is connected by a conductor 81 with coils 81^a of magnet 81^b and the other terminals of these coils is connected by a conductor 81^c with contact shoe 33. The other terminal of 90 relay 53 coil is connected by a conductor 82 with one terminal of the coil of relay 54, the other terminal of the latter being 95 connected by a conductor 83 with a conductor 84 and this conductor is connected at one end with the contact rod 40. One terminal of the coil of relay 55 is connected by a conductor 85 with a conductor 86, the 100 latter being connected at one end with one terminal of the coil of relay 57 and at the other end with one terminal of coils 81^d on magnets 81^b and the other terminal of these coils is connected by a conductor 86^a with 105 contact shoe 34. The other terminal of the coil of relay 55 is connected by a conductor 87 with one terminal of the coil of relay 56 and the other terminal of the latter is connected, by a conductor 88, with the truck 110 frame as indicated at 89. The other terminal of the coil of relay 57 is connected by a conductor 90, with one terminal of the coil of relay 58, and with the other terminal of the latter, one end of a conductor 91 is connected. The other end of this conductor is connected with the cam plate 39 on the speedometer shaft and includes in its circuit a high resistance electro-magnet 92.

115 An electro-magnetically operated brake 1

valve is indicated at 93 and is preferably such as will effect the gradual application and release of the brakes. One terminal of the electro-magnet 94 of this valve mechanism is connected by a conductor 95 with the positive pole of a battery 96, the other pole of this battery being connected by a conductor 97 with the conductor 91. The other terminal of the coil of magnet 94 is connected by a conductor 98 with a conductor 99. The conductor 99 is connected at one end with the contact rods 41, 42, 43, 44 and 45, and at the other end with the conductor 91 and includes in its circuit, a normally open circuit closer 100. The movable member of this circuit closer is normally held out of engagement with the stationary contact, by a latch 101 controlled by the magnet 92.

20 The magnets 81^b control an armature lever 102 which constitutes a latch for a signal block 103. The armature lever also forms the movable member of a circuit closer 104 included in a normally open circuit 105 with a battery 106 and an audible signal 107.

My improved system may be operated as follows:—Let it be assumed that a train is approaching the ten-mile curve illustrated in Fig. 4 at a speed less than ten miles an hour and that the contact shoe 33 has engaged the contact rail 6. Under these conditions, the circuits would be established. From battery 4 to conductor 5, to contact rail 6, shoe 33, to conductor 81^c, through magnet coils 81^a, to conductor 81, to relay 53, to conductor 82, to relay 54, to conductor 93, to conductor 84, to conductor 88, to truck frame 89, to track rail 1 to conductor 3 to battery 4. The current in this circuit 40 will energize magnets 81^b and operate armature lever 102 to trip the visual signal 103 and close the local circuit including the audible signal 107. If the train be running at a speed greater than ten miles an hour, the 45 shaft of the speedometer will have turned sufficiently to bring the cam disk 39 in line with the contact rod 40. Under these conditions, when the contact shoe 33 engages the contact rail 7, both batteries 4 and 9 50 will be included in series with each other, and the following circuits will be established:—From battery 4, to conductor 10, through battery 9, to conductor 8 to contact rail 7, to shoe 33, to conductor 81^c to conductor 91, at which point the circuit divides, one branch including the magnet coils 81^a and relay coils 53—54, as before described, and the other branch may be traced by way of conductor 91 (including magnet 92) to 55 cam disk 39. The energizing of the relay 53 by the current in the first-mentioned branch of the circuit, will close the local circuit including battery 66 and magnet 47, thus energizing the latter so that the contact rod 40 will be projected into engage-

ment with the cam disk. The tracing of the second branch of the circuit may now be continued from cam disk 39 to contact rod 40, to conductor 84, where the two branches of the circuit unite, and the remainder of the circuit may then be traced by conductor 88 to truck frame 89 to track rail 1, to conductor 3 to battery 4. Thus it will be seen that when a shoe 33 engages contact rail 7, the magnet coils 81^a and 75 coils of relays 53—54 will be included in parallel with the magnet 92. The energizing of the high resistance magnet 92 in one of these circuit branches will cause the release of the movable member of the circuit closer 100 and thus effect the closing of a circuit which may be traced as follows: From battery 96 to conductor 95, through brake valve magnets 94, to conductor 98, to conductor 99, through circuit-closer 100 to 80 conductor 91 to conductor 97 to battery 96. The current in this circuit will energize the valve magnets 94 and cause the operation of the valve to apply the brakes and stop the train. Assume now that the train is approaching the twenty-mile curve shown in Fig. 5, at a speed greater than twenty miles an hour. When the contact shoe 33 engages the contact rail 14, the same circuit as first above described through the magnet coils 81^a 95 and relays 53—54 will be established, except that the path of the current will be reversed,—the positive pole of the battery for the track circuits being connected to track rail and the negative pole to the contact rail in Fig. 5. In consequence of this, the armature lever of the polarized relay 53 will not be moved and hence the circuit of magnet 47 will be kept open, but the polarized relay 54 will move its armature lever and close the local circuit including the battery 66 and magnet 48, thus causing the contact rod 41 to be projected into engagement with the cam disk 39, which, at this time will have been sufficiently turned by reason of the speed of the train, to be in position to receive said contact rod 41. Engagement of the contact rod 41 with cam disk 39 will close a local circuit as follows: From battery 96 by conductor 95 to valve magnets 94, to conductor 98 to conductor 99, to contact rod 41, to cam disk 39, to conductor 91, to conductor 97, to battery 96. The current in this circuit will energize the magnets 94 and start the operation of the brake valve. The operation of this valve will cause the gradual application of the brakes to check the speed of the train. When the speed of the train shall have been reduced below twenty miles an hour, the local circuit of the battery 96 and brake valve magnets 94, will be opened by the retrograde movement of the cam disk out of engagement with the contact rod 41,—thus deenergizing the brake valve magnets and permitting the 110 115 120 125 130

gradual release of the brakes. As the contact rail 14 extends around the curve, the brakes would be again applied if the train should exceed a speed of twenty-miles an hour while traveling on the curve.

When a train approaches the thirty-mile curve, Fig. 6, the contact shoe 34 engages the contact rail 18, a circuit will be established as follows: From positive pole of battery 16, 10 to conductor 17, to contact rail 18, to shoe 34, to conductor 86^a, to magnet coil 81^b, to conductor 86, to conductor 85, to coil of relay 55, to conductor 87, to coil of relay 56 to conductor 88 to truck frame 89, to track rail 1, 15 to conductor 15 to negative pole of battery 16. This will cause the closing of the local signal circuit 105 as before explained and the energizing of the polarized relays 55 and 56. The armature lever of the relay 56 will not 20 be moved, but the armature lever of the relay 55 will be shifted to close the local circuit including the battery 72 and magnet 49, thus causing the contact rod 42 to be projected into contact with the cam disk 39, 25 which latter has been moved (by reason of the speed of the train) sufficiently to be in position to receive said contact rod. Engagement of the contact rod 42 with the cam disk will close the local circuit of the 30 battery 96 and brake valve magnets 94 as previously explained, and cause the operation of the brakes in the same manner as above stated in describing the control of the brakes at the twenty-mile curve.

25 At the forty-mile curve (Fig. 7) the circuit connections of the battery are the reverse of those shown in Fig. 6,—that is to say, in Fig. 7 the positive pole of battery 20 is connected with the brake rail and the
40 negative pole is connected with the contact rail 22. Thus when the shoe 34 of the train engages the contact rail 22 (for the forty-mile curve) the direction of the current through the circuit including the coils of
45 relays 55—56 will be reverse to that above described, resulting in the shifting of the armature lever of relay 56 instead of relay 55 and the energizing of magnet 50 to project the contact rod 43 into engagement with
50 the cam disk for closing the local circuit which controls the brake valve devices.

For each of the fifty and sixty-mile curves, two parallel contact rails are employed to cooperate with the two shoes 33 and 34 on the rolling equipment. In Fig. 8 which shows the fifty-mile curve, the positive pole of the battery 26 is connected with the contact rail 24 and the negative pole is connected with the contact rail 23, while in the arrangement shown in Fig. 9, (showing the sixty mile curve) these connections are reversed,—viz. in said Fig. 9, the positive pole of battery 31 is connected with the inner contact rail 3.

65 When a train approaches the fifty mile

curve the contact shoes 33 and 34 will engage both contact rails 23-24, and establish circuits as follows:—From positive pole of battery 26 to contact rail 24, to shoe 34, to conductor 86^a to magnet coils 81^b to conductor 86, to coil of relay 57, to coil of relay 58, to conductor 91, to conductor 81^c, to shoe 33, to contact 23 to negative pole of battery. The current in this circuit will cause the relay 57 to shift its armature lever (the armature lever of relay 58 remaining stationary) and close the local circuit of battery 77 and magnet 51 to project contact rod 44 into engagement with the cam disk 39 for establishing the circuit of the battery 96 and brake valve magnets 94 as previously explained.

When the contact shoes 33—34 bridge the contact rails 28—29 at the sixty-mile curve, Fig. 9, the same circuits through the coils of relays 57—58 as above described will be established, except the current direction will be reversed and hence the relay 58 will now shift its armature lever (the armature lever of relay 57 remaining stationary) to close the local circuit of magnet 52 and project the contact rod 45 to engage the cam 39 and close the circuit of the brake valve controlling means.

It will be observed that at all curves, the visual and audible signals will be operated; that at the ten mile curve the train will be brought to a full stop and that at all other curves, the speed of the train will be checked to a predetermined speed and kept at such predetermined speed until the train shall have passed the curve. 95 100.

Various slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

1. In an electrical train control system, the combination with a railroad, rolling equipment, and speed-controlling means on the rolling equipment, of electrical means for controlling said speed-controlling means, electrical selecting means on the rolling equipment for controlling said electrical means, speed-responsive means operatively connected with said selecting means, and a plurality of partial electric circuits along the railroad and means for connecting said partial circuits with circuits of the electrical selective mechanism on the rolling equipment. 115 120

125
2. In an electric train control system, the combination with a railroad, rolling equipment, and speed-controlling means on the rolling equipment, of electrical mechanism on the rolling equipment for controlling 130

- 5 said speed controlling means, a speedometer operatively connected with the rolling equipment connections between the speedometer and said electrical mechanism for controlling the latter, and electrical means along the railroad coöperating with the speedometer connections and with said electrical mechanism for controlling the latter in accordance with the speed and position of the 10 rolling equipment.
- 10 3. In an electric train control system, the combination with a railroad, rolling equipment, and brake-controlling means, of electrically controlled mechanism on the rolling equipment for governing said brake-controlling means, a speedometer operatively connected with the rolling equipment for controlling the operation of said electrically controlled mechanism, and electrical means 15 arranged along the railroad for coöperation with said speedometer and said electrically controlled mechanism for controlling the operation of the latter to control the brake-controlling means according to predetermined speeds and positions of the rolling 20 equipment.
- 20 4. In an electric train control system, the combination with a railroad, a rolling equipment, brake controlling means on the rolling 25 equipment, and electro-magnetically controlled means for controlling the operation of said brake controlling means, of a speedometer on the rolling equipment, an electric circuit including said electro-magnetically controlled means and a plurality of contacts arranged to be closed successively by the speedometer, a plurality of electro-magnetically controlled devices for controlling the relation of said contacts to the speedometer, and means for controlling the operation of the last-mentioned electro-magnetically controlled devices, whereby the speed of the rolling equipment will be varied and controlled.
- 45 5. In an electric train control system, the combination with a railroad, a rolling equipment, brake controlling means on the rolling equipment, and electro-magnetically controlled means for controlling the operation of said brake controlling means, of a speedometer on the rolling equipment, a contact member movable by the speedometer, a plurality of contacts for said contact member, normally open circuits including said 50 contacts and contact member and said electro-magnetically controlled means, partial circuits at different points along the railroad, and electrically controlled means on the rolling equipment and coöperatively related to said partial circuits for controlling the operative relation of each of said con-

65 tacts to the contact member of the speedometer.

6. In an electric train control system, the combination with a railroad, a rolling equipment, brake controlling means therefor, an electro-magnetically controlled means for controlling the operation of the brake controlling means, of a speedometer on the rolling equipment, a contact member movable by the speedometer, a plurality of movable contacts to coöperate with said contact member, normally open electric circuits including said contacts, contact member and the electro-magnetically controlled means of the 70 brake controlling means, electro-magnets for moving each of said contacts into operative relation to said contact member, relays for controlling the circuits of the several magnets, partial circuits on the rolling 75 equipment including said relays and partial circuits at different points along the railroad and each having coöperative relation to the partial circuit of one or another of said relays, whereby the movable contacts will 80 be moved into electrical relation to the contact member according to the speed of the rolling equipment.

85 7. In an electric train control system, the combination with a railroad, rolling equipment, brake controlling means, and electro-magnetically controlled means for controlling the operation of the brake controlling means, of a speedometer on the rolling equipment, a contact member movable by the speedometer, a plurality of movable contacts to coöperate with said contact member, normally open electric circuits including said contacts, contact member and the electro-magnetically controlled means of the 90 95 brake controlling means, partial electric circuits along the railroad, means on the rolling equipment having coöperative relation to said partial circuits for controlling the movements of said contacts, a normally 100 open circuit on the rolling equipment including the electro-magnetically controlled means of the brake controlling means, a normally open circuit closer in said circuit, an electro-magnetically controlled device for said circuit closer, and a partial circuit including the magnet of said last mentioned electro-magnetically controlled device and coöperatively related to a partial circuit along the 105 railroad.

110 In testimony whereof, I have signed this specification in the presence of two subscribing witnesses.

115 ANDREW J. ALLARD.
